UNITED STATES PATENT OFFICE.

STEPHEN D. TUCKER, OF NEW YORK, N. Y.

WEB PRINTING AND DELIVERY MECHANISM.

SPECIFICATION forming part of Letters Patent No. 367,123, dated July 26, 1887.

Application filed April 27, 1882. Serial No. 50,747. (No model.) Patented in England October 3, 1881, No. 4,285.

To all whom it may concern:

Be it known that I, STEPHEN D. TUCKER, a citizen of the United States, residing in the city of New York, county of New York, State 5 of New York, have invented certain new and useful Improvements in Web Printing and Delivery Mechanism, (the said improvements being embraced in British Letters Patent No. 4,285, granted to William Conquest, October 10 3, 1881,) fully described and represented in the following specification and the accompanying drawings, forming a part of the same.

The present invention relates to that class 15 of web-printing machines in which the forms for printing both sides of the web are carried upon a single cylinder, and in which the web after being printed upon one side is turned over and re-presented to the same forms to be printed upon its opposite side, the travel of 20 the web between the printing of its opposite sides being so distanced that when the web is perfected the printed pages for one side of the sheet upon one side of the web will register with the pages for the opposite side of the 25 sheet upon the opposite side of the web, and vice versa.

It will readily be seen that the sheets severed from a web perfected in this manner will not pass to the delivery mechanism in a uniform position, but that one half of said sheets 30 will have their outside pages uppermost, while the other half will have their inside pages uppermost; and it will also be seen that, if the columns of the forms lie lengthwise of the form- 35 cylinder, (which is usually the case in this class of machines,) in addition to this the heads of one half of the sheets will be at one side of the machine while the heads of the other half will be at the opposite side. These facts make 40 it necessary, in order to pile the sheets in regular and proper order, to direct them to two flies, or, if they are to be folded, to two folding mechanisms.

The present invention consists in the combination, 45 with the type or form cylinder and impression - cylinders and a web - turner arranged to co-operate therewith to print both sides of a web from the same forms, of a mechanism for severing the web into sheets and a 50 collecting mechanism arranged to associate the sheets into lots, each of which lots shall con-

tain sheets upon which the pages are printed in like order, all substantially as hereinafter described.

The invention also includes the combination, 55 with the type or form cylinders carrying forms for printing both sides of the web, one-half of said forms being placed at each end of the cylinder, of impression-cylinders and web-turning mechanism arranged to co-operate therewith to print both sides of the web from said forms, and mechanisms for splitting the web longitudinally into sections and for severing said sections into sheets, all substantially as 60 hereinafter described.

The invention also embraces various other details of construction and combinations of parts, all of which will be hereinafter fully described and particularly claimed in connection with the accompanying drawings, in which— 70

Figure 1 is a side elevation of a web printing and delivery mechanism embodying the present invention. Fig. 2 is a longitudinal vertical section of the same. Fig. 3 is an end elevation of the same, looking from the right 75 of Figs. 1 and 2, the parts at the right of the form-cylinder being removed. Fig. 4 is a like view of a double-width machine. Fig. 5 is a plan view of the web-turner by which the web is turned over between the printing of its opposite sides. Fig. 6 is a diagrammatic section 80 illustrating the manner in which the single-width printing mechanism is operated to produce two-page or half-sheet papers or supplements. Fig. 7 is a like view illustrating the 85 manner in which the double-width printing mechanism is operated to produce four-page papers or supplements. Fig. 8 is a view of a single-width web, showing the order in which the pages will occur when it is printed for a 90 four-page paper. Fig. 9 is a similar view showing the order in which the pages will occur when said web is printed for a two-page or half-sheet paper or supplement. Fig. 10 is a view 95 of a double-width web, showing the order in which the pages will occur when it is printed for an eight-page paper; and Fig. 11 is a similar view showing the order in which the pages will occur upon said web when it is printed for a four-page paper or supplement.

The printing mechanism illustrated in the accompanying drawings is a double one—that 100

is to say, is adapted to operate simultaneously upon two webs of paper. This feature is not material, however, as the invention is equally applicable, as will hereinafter fully appear, to 5 a printing mechanism which operates upon only a single web.

The construction of the mechanism in connection with its operation upon one of the webs will be first described, after which those 10 parts which are added to capacitate it to operate upon the second web will be pointed out, and, as far as may be necessary, described.

The type or form cylinder 5, which is of the usual construction and of a size sufficient to 15 permit ordinary type to be securely fastened to its periphery, is mounted in bearings in a suitable frame, and, as here shown, is provided with four forms of type, 1 2 3 4, which for convenience it will be assumed are of the 20 proper size for printing the four pages of an ordinary folio or four-page newspaper. These forms are, as is usual when printing from type, arranged so that their columns of matter lie longitudinally of the cylinder, and are, as 25 shown, arranged in pairs located diametrically opposite each other upon the cylinder, each pair occupying one-fourth of its circumference. The spaces upon the cylinder between the 30 groups of forms are occupied by ink-distributing tables or surfaces 6, to which the ink is supplied from an ordinary ink-fountain, (not shown,) and from which it is taken and applied to the forms by ordinary inking-rolls, 20, as in the well-known Hoe type-revolving 35 press.

As has just been explained, the forms do not cover the entire surface of the type or form cylinder, and this is due to the fact that in order to successfully secure ordinary type to a 40 cylinder it is necessary that such cylinder should be of so large a size that the forms for printing an ordinary newspaper will not be sufficient to cover its whole circumference. It therefore becomes necessary in this class of 45 machines, in order to print the whole surface of the web, that each form should act more than once upon the web at each revolution of the form-cylinder. This is accomplished by providing a plurality of impression-cylinders 50 and a register roll or rolls for each side of the web, the number of such impression-cylinders and register-rolls being determined by the proportion of the surface of the form-cylinder that is occupied by the forms. In the 55 present case the forms, as just stated, occupy one-half of the circumference of the form-cylinder, and there are therefore provided two impression-cylinders and one register-roll for each side of the web.

60 The web to be printed is led from a roll, 7, and after passing beneath a guide-roll, 8, passes around the impression-cylinder 9, thence outward around the register-roll 10, and thence inward around the second impression-cylinder, 11. In passing the cylinder 9 the web will receive impressions from the forms 4 and 1, and the part bearing these impressions

will then pass around the roll 10, while the forms 4 and 1 will pass onward and give a second impression to that portion of the web passing over 70 the cylinder 11. The roll 10 is placed at such a distance from the type-cylinder that the advance end of the impression given by form 4 upon cylinder 9 will arrive upon cylinder 11 just in time to exactly join with the rear edge 75 of the impression given by form 1 upon that cylinder. From this it will be seen that this pair of forms makes two impressions upon the web in succession, the second impression being just in advance of the first. Following 80 the rear edge of the impression made by form 1 upon cylinder 9 will be a blank space equal to the space upon the type-cylinder between forms 1 and 3, which space is just equal to the length of a pair of forms. At the end of this 85 space the forms 3 and 2 will make impressions upon the web upon cylinder 9, and, passing to cylinder 11, will make second impressions just in advance of the first, which second impressions will just fill the blank space referred to. 90 This operation being repeated at each revolution of the type-cylinder, one side of the web will be wholly covered, the impressions of each pair of forms occurring twice in succession—as 4 and 1, 4 and 1, 3 and 2, 3 and 2, 4 and 95 1, &c.—as shown in Fig. 8. After passing impression-cylinder 11, the web, now printed upon one side, is conducted around guide-rolls 12, 13, 14, and 15 and a web-turner onto the third impression-cylinder, 16. 100

The web-turner, as shown, is composed of a leading-roll, 19, and fixed bars 17 18, arranged at right angles to each other and obliquely across the path of the web. (See Fig. 5.) In order to turn over or reverse the web, so as to 105 present its unprinted side to the type, it is led under and around bar 17, thence laterally and downward around roll 19, and thence inward and upward around bar 18, thus bringing its 110 printed side uppermost, as shown in Fig. 5, and next to the impression-cylinder, and consequently its blank side to the type.

The roll 14 is journaled in the ends of arms 23, extending from the rock-shaft 24, which is provided with a worm-gear, 25, and controlled by a worm, 26, so as to effect a nice adjustment of the roll 14, to vary to any desired extent the distance traveled by the web between the cylinders 11 and 16 in order to secure the proper registrations between the impressions upon its opposite sides. After passing cylinder 16 the web passes outward around the register-roll 21, and thence returns inward and passes around cylinder 22. The operation of the forms upon the type-cylinder, in connection 120 with impression-cylinders 16 and 22, to print the side of the web now presented, is exactly the same as that already described in connection with cylinders 9 and 11 in printing the first 125 side of the web, and therefore needs no specific 130 description.

The distance traveled by the web between the cylinders 11 and 16 is so regulated by the position of the roll 14 that the impressions

made by the forms 3 and 2 upon the second side of the web will be opposite those made by the forms 4 and 1 upon the first side, and vice versa, and the forms 4 and 1 are placed upon the cylinder with their columns headed in the opposite direction to that of the columns of the forms 3 and 2, (see Fig. 8,) so that after the web is turned over the columns of the registering impressions upon its opposite sides will be headed in the same direction.

In printing the web by a mechanism such as just described it will be observed that no one of the impression-cylinders is continuously in contact with the forms, and, that there are 15 times when at least three, and if they are mounted in a slightly different relation to each other from that shown, even all four, of the impression-cylinders will be out of contact with the forms. This intermittent action of the

20 printing devices has been found to cause such an irregular feeding of the web, when, as has heretofore been customary, the printing mechanism has been depended upon for that purpose, that it is impossible to secure accurate 25 registration between the different impressions.

To cure this defect and to give a positive and uniform feed to the web, the rolls 10 and 21 are provided with coating-forwarding-rolls 27 and 28, which are provided with yielding 30 peripheries, and preferably so placed as to bear upon the margins of the web. The shafts of the rolls 27 and 28 are supported in sliding journal-boxes, which are pressed by springs controlled by set-screws, so that any desired 35 degree of pressure on the web may be obtained. The roll 21 is positively driven from the impression-cylinder 22 through intermediates 31 and 32, and the roll 10 from the driving-shaft through intermediates 29 and 30. The forward-

40 ing-rolls 27 and 28 may be geared to the rolls 10 and 21, or not, as may be found desirable. The feeding devices just described are not, however, herein claimed, as they are the invention of another.

45 After receiving its final impression upon the cylinder 22, the web passes between the cutting-cylinders 33 and 34, by which it is partially severed upon the lines $z z$, (see Fig. 8,) and into the bite of the two series of tapes 35 and 36, 50 which are accelerated in the usual manner to part the sheets from the web. The upper set, 35, of these tapes pass around pulleys 37, over pulleys 38, under pulleys 39, over pulleys 40, thence downward inside of pulleys 41 and 55 around roll 42, returning over pulleys 43. The under set, 36, pass around pulleys 44, over pulleys 38, thence around the gathering or collecting cylinder 45 and over pulleys 40, thence downward inside of pulleys 46, outside of pulleys 47 and roll 48, and inside of roll 49, returning around pulleys 50 and roll 51. Co-operating 60 with the tapes 35 and 36 are two sets of supplemental tapes, 52 and 53. The set 52 pass around pulleys 54 and downward around pulleys 55, returning outside of roll 56. The set 53 pass around pulleys 47 and roll 48, above roll 49, and around roll 57, returning inside of pulleys

55 and outside of roll 56. The sheets, after being parted by the tapes 35 and 36, pass downward around pulleys 38, and are by the fixed 70 guides 58 conducted onto the gathering-cylinder 45, which operates in the well-known manner to associate the sheets in pairs. When a pair of sheets have been associated, they are guided off the cylinder by the switches 59, 75 which are operated at every second revolution of the cylinder by the cam 60 and its connections in the usual manner. The pair of sheets thus thrown off the cylinder will pass over the pulleys 40 and downward between the pulleys 80 41 and 46, when they will be deflected by the switches 61, so as to pass between pulleys 46 and 47 and into the bite of the tapes 36 and 53, by which they will be carried downward until they issue from between rolls 49 and 57 in front of the 85 fly, by which they will be flown in the usual manner. When the next pair of sheets pass from the cylinder 45, the switch 61 will have been shifted, so that they will be guided between pulleys 41 and 54 and issue from between 90 roll 42 and pulleys 54 and pass downward with tapes 52 in front of the upper fly, to be flown in like manner. The parts will be so timed that each pair of sheets associated by the cylinder 45 will consist of the two sheets which 95 have the same printed matter upon their upper sides—that is to say, the sheets having pages 4 1 upon their upper sides will be associated to form one pair, those having pages 3 2 to form the next pair, and those having pages 100 4 1 to form the third pair, &c. From this it will result that as the alternate pairs go to different flies all the sheets delivered by each fly will have the same side uppermost, and the heads of the columns will all be at the same 105 side of the pile.

The type-cylinder in machines of the class just described is not always made of such a size that the forms cover one-half of its circumference. The proportion of the circumference of the cylinder occupied by the forms will depend upon the number and size of the forms, and the number of the impression-cylinders and register-rolls will be governed by the proportion of the circumference of the cylinder covered by the forms; but the gathering-cylinder will be operated in all cases so that the sheets having their columns headed in the same direction will be associated and sent to the same fly. It is the attainment of 110 this desirable result that makes the herein-described delivery apparatus particularly applicable to a printing mechanism of this class.

The shaft of the switch 61 is provided with an arm, 62, to which is connected the rod 63, the lower end of which engages with a cam of suitable form upon the transverse shaft 64, by which the switch is operated at the proper times. The shaft 64 is driven through bevel-gears 66 and 67 from the longitudinal shaft 68, 115 which receives its motion from the driving-shaft through worm and worm-gear 70 and 71. The shaft 64 is also provided with cams, which, through suitable connections, as shown in Fig.

1, operate the flies in the usual manner. The type and impression cylinders are driven by connecting-gears in the usual manner, motion being communicated to them through gear 29 5 from gear 69 upon the driving shaft.

The various sets of tapes, as well as the gathering-cylinder, are driven by suitable connecting-gears, motion being communicated to them from the cutting-cylinders through the 10 train of intermediates 65, the cutting-cylinders themselves being driven from impression-cylinders 22 through intermediates 31.

In order to double the capacity of the machine, it may, as shown in the present case, 15 be provided with a second set of impression-cylinders and delivery apparatus located upon the opposite side of the type-cylinder. These mechanisms are exact duplicates, both as to 20 construction and operation, of those already described, except that they are located differently with relation to the type-cylinder. The roll 72, from which the second web is led, and the first pair of impression-cylinders and register-roll 73, 74, and 85 are located at the top instead of at the bottom of the machine, and the 25 second pair of impression-cylinders and register-roll 75, 76, and 86, web-turners 77, 78, and 79, cutting-cylinders 80 and 81, tapes 82 and 83, and gathering-cylinder 84 are correspondingly reversed in position.

In the use of all web-printing machines, and particularly of those of the character herein shown, considerable delay has been occasioned by the difficulty experienced in "threading" 35 or passing the leading end of the web through the machine. To facilitate the threading, these machines have been provided with tapes which followed the course of the web through the machine, and were arranged to bear only upon 40 the margins of the web, so as not to interfere with the printing. While tapes so arranged operated satisfactorily in threading the machine, it was found in practice that they caused the web to wrinkle more or less, and 45 that consequently it was very undesirable to have them in contact with the web while the printing was in progress. This difficulty is avoided in the present invention by placing the threading tape or tapes outside the 50 margins of the web, so that while the printing is in progress the tape or tapes and the web will be entirely disconnected. For this purpose the machine is provided with the tape 87, which passes around guide-roll 8 just outside 55 the edge of the web, at one side of the machine, (see Figs. 2 and 3,) follows the course of the web through the first printing mechanism and to the web-turner, then around the web-turner, by which it is transferred to the opposite side 60 of the machine, (see Fig. 5,) then with the web through the second printing mechanism and into the bite of the tapes 35 and 36. From this point it passes around rolls 88, 89, 90, and 91, and again around roll 8, but on the opposite 65 side of the machine from that at which it entered. From this point it again follows the course of the web through the first printing

mechanism to the turner, then again around the turner, by which it is transferred back to the side of the machine from which it started, 70 after which it passes again through the second printing mechanism and around the guide-rolls 88, &c., back to the point of starting.

When the leading end of the web is to be conducted through the machine, a stout thread, 75 92, is made fast to the tape at one side, and is then passed in and out across the end of the web in a series of stitches and made fast to the tape at the other side, as shown in Fig. 3. The machine being then started slowly, the end of 80 the web will be carried forward by the tape and introduced through the entire printing mechanism. When the end of the web has been carried into the bite of the tapes 35 and 36, the threading is complete and the thread 92 85 is removed or detached from the tape at both sides of the web.

By means of the tape arranged as just described, it will readily be seen that the web can be led through the machine as desired, 90 and yet the tape be entirely free from the web during the printing, so that all wrinkling is prevented.

When tapes are used which press upon or grasp the margins of the web, it is necessary to employ two sets, one for each surface; but by the present system only one tape or pair of tapes is or are necessary, and thus one-half the tapes and a portion of the rolls for guiding them are dispensed with.

When a web-turner is used so that the tape will be crossed, as in the present case, a single tape only is necessary, as has been shown; but where a web-turner is not used it will of course be necessary to employ two tapes, one for each 105 side of the machine.

A tape, 93, corresponding to the tape 87 and passing around rolls 98, 99, 100, and 101, is employed in the duplicate printing mechanism at the right of the type-cylinder, as shown 110 in Figs. 6 and 7.

When it is desired to produce only folio or four-page papers, the various cylinders, rolls, &c., of the mechanism just described will be of a length suitable for operating upon a single-width web, as shown in Fig. 3; but if it is desired to capacitate the machine to produce quarto or eight-page papers the parts will be made of double such length, so as to be capable of operating upon a double-width web, as 120 shown in Fig. 4. In the latter case the forms will be placed upon the type-cylinders with the heads of the columns lying together at the center, one group of forms containing matter for pages 8 1 and 5 4, and the other group 125 matter for pages 6 3 and 7 2, so that the web will be printed as shown in Fig. 10. The web will be severed upon the lines *x x*, and the corresponding pairs of sheets associated and delivered in the manner already described.

When it is desired to produce two-page papers or supplements on a single-width machine, it may be done by the arrangement shown in Fig. 6. The type-cylinder, instead of car-

rying four forms, will of course carry two, and these will be placed upon opposite sides of the cylinder. One of these forms will contain matter for page 5 if, for example, the product is to be a supplement for a four-page paper, and the other will contain matter for page 6. The web will be led from the roll 7 over the cylinders 9 and 11, where it will receive two impressions from each of the two forms upon the type-cylinder, which impressions will be separated by blank spaces equal to the width of the forms removed. The web will then be turned and receive the same impressions upon its opposite side while passing around cylinders 16 and 22, page 6 falling opposite to page 5, and vice versa. After this it will be led over adjustable guide-rolls 94 and 95 and around cylinders 73 and 74, where it will again receive the same impressions upon the same side. The rolls 94 and 95 are, however, so adjusted that the web in passing over them will travel such a distance that the impressions received upon cylinders 73 and 74 will cover the blank space between the impressions received upon cylinders 16 and 22, so that one side of the web will now be entirely printed, the impressions occurring in the order shown in Fig. 9—that is to say, there will be four pages 5, followed by four pages 6, &c. After passing cylinder 74, the web is turned and passes around cylinders 75 and 76, where the printing of the first side is completed by filling in the blank spaces left in passing cylinders 9 and 11. The web now passes between the cutting-cylinders 80 and 81, which, in addition to the severing-blade 96, are supplied with a perforator, 97, so that the web will be severed upon the lines *y y* and perforated upon the lines *v v*. After this the sheets will be associated in pairs and delivered to the flies in the manner already set forth. The sheets in this case will each contain two supplements, which can, by reason of the lines of perforations, be readily torn apart by hand when desired. In threading the machine in this case the end of the web will be fastened to the tape 87, by which it will be led forward until it has passed around cylinder 22, when it will be detached from the tape 87 and carried over rolls 94 and 95 to tape 93, to which it will be secured, and which will conduct it through the second printing mechanism to the bite of the tapes 82 and 83.

The operation of the machine in producing folio or four-page papers from a single-width web has already been explained. If, however, it is desired to produce four-page papers or supplements from a double-width web, it may be done by arranging and operating the double-width machine in the manner illustrated in Fig. 7.

The forms for printing the four pages will be placed upon the type-cylinder in a single group, and a dummy, 102, will be placed opposite to properly balance the cylinder. The forms for printing the first and fourth pages of the paper or supplement—or, in other words, the forms for printing one side of the sheet—will be placed side by side upon one end of the

type-cylinder, and those for printing the second and third pages—that is to say, the other side of the sheet—will be placed upon the other end of the cylinder, the heads of the columns of all the forms being at the center of the cylinder. If, as illustrated in Fig. 11, a supplement for an eight-page paper is to be produced, the forms for printing pages 9 12 will be upon one end of the cylinder and the forms for pages 10 11 upon the other. A double-width web will then be led from the roll 7, and in passing over cylinders 9 and 11 will receive two impressions, as *a b*; but, there being no forms upon the opposite side of the type-cylinder, the spaces *c d* will be left blank, after which blank spaces will follow impressions *e f*, made by the forms at the next revolution of the type-cylinder. The web, after passing cylinder 11, will be turned, and in passing cylinders 16 and 22 will receive the same impressions upon its opposite side. The turning of the web, as will be readily understood, will cause pages 9 12 to be printed opposite to pages 10 11, and vice versa. After leaving cylinder 22 the web will be led around rolls 94 and 95 to cylinders 73 and 74, where the spaces left blank in passing cylinders 16 and 22 will be printed, after which it is again turned and led to cylinders 75 and 76, where the spaces *c d* left blank in passing cylinders 9 and 11 will receive impressions, which will complete the printing of the web. The web thus printed will be split upon the line *u u* by a slitter, as 300, located at any convenient point, and then severed upon the lines *w w* by the cutting-cylinders, after which the sheets will be associated and delivered in the manner already described.

By reference to Fig. 11 it will be observed that when a double-width web is perfected in this manner and then split longitudinally into two sections the sections are duplicates as to printed matter, but that the pages upon the under side of one section are upon the upper side of the other, and vice versa, and also that each section contains a series of complete sheets or products, all the sheets of each section having the same pages uppermost. It will also be observed that by this means four-page papers or products can be produced from a single double-width web without duplicating the forms and with the same rapidity that they can be produced from two webs upon a single-width machine operated at the same speed. When this product is being produced, two pairs or lots of associated sheets will of course pass side by side to each of the flies, and the sheets will be laid in two side-by-side piles upon the tables; but all the sheets of each pile will have the same pages uppermost, so that no confusion will be occasioned.

What I claim is—

1. The combination, with the type or form cylinder 5 and impression-cylinders, and a web-turner arranged to co-operate therewith to print both sides of a web from the same forms, of a mechanism for severing the web into sheets and a collecting mechanism ar-

- ranged to associate the sheets into lots, each of which lots shall contain sheets upon which the pages are printed in like order, all substantially as described.
- 5 2. The combination, with the type or form cylinder 5 and impression-cylinders, and a web-turner arranged to co-operate therewith to print both sides of a web from the same forms, of a mechanism for severing the web into sheets, a collecting mechanism arranged to associate the sheets into lots, each of which lots shall contain sheets upon which the pages are printed in like order, and means for directing the different lots to separate piling mechanisms, all substantially as described.
- 10 3. The combination, with a web-printing mechanism in which the same form makes a plurality of impressions upon the same side of the web at each revolution of the type or form cylinder, of a web-severing mechanism, a mechanism for associating like sheets together, and means for directing the lots of associated sheets into different pathways, all substantially as described.
- 15 4. The combination, with a web-printing mechanism in which the same form makes a plurality of impressions upon the same side of the web at each revolution of the type or form cylinder, of a web-severing mechanism, a mechanism for associating like sheets together, means for directing the lots of associated sheets into different pathways, and two piling mechanisms for piling the sheets emerging from the different pathways, all substantially as described.
- 20 5. The combination, with the type or form cylinder 5, two sets of impression-cylinders, each set consisting of a plurality of cylinders, a web-turner, and suitable register-rolls, as 10 and 21, of a web-severing mechanism and a collecting mechanism arranged to associate the sheets into lots, each of which lots shall contain sheets upon which the pages are printed in like order, all substantially as described.
- 25 6. The combination of the type or form cylinder 5, carrying the forms for printing both sides of a web, with sheets which occupy only half the width of the web, the forms for printing the pages on one side of the sheet being placed at one end of the cylinder and those for printing the pages on the other side of the sheet at the other end of the cylinder, with the heads of their columns pointing in the opposite direction, impression-cylinders and web-
- turning mechanism arranged to co-operate 55 with said form-cylinder to print both sides of the web from said forms, and mechanism for slitting the web longitudinally into two sections and for severing said sections transversely into sheets, whereby there are produced from a single wide web duplicate side-by-side streams of papers, all substantially as described.
7. The combination of the type or form cylinder 5, carrying the forms for printing both sides of a web, with sheets which occupy only one half the width of the web, said forms being arranged in a single group, with those for printing the pages on one side of a sheet at one end of the cylinder and those for printing 60 pages on the other side of the sheet at the other end of the cylinder, with the heads of their columns pointing in the opposite direction, impression-cylinders and web-turning mechanism arranged to co-operate with said form-cylinder to print both sides of the web from said forms, and mechanism for slitting the web longitudinally into two sections and for severing said sections transversely into sheets, whereby there are produced from a single wide 65 web duplicate side-by-side streams of papers, all substantially as described.
8. The combination, with the type or form cylinder 5 and the four sets of impression-cylinders and co-operating register-rolls and web-turners, of guide-rolls, as 94 and 95, substantially as described.
9. In a web-printing mechanism, a threading-tape located just outside of each edge of the web and following its course through the 70 machine, substantially as described.
10. The combination, with the type or form cylinder 5, provided with co-operating impression-cylinders and web-turners, by which it is capacitated to simultaneously perfect two 75 webs from the same forms, of leading-rolls which are so arranged that when one of said webs is omitted the other can be led to and operated upon by all of said impression-cylinders and web-turners, all substantially as described.
- In testimony whereof I have hereunto set my hand in the presence of two subscribing witnesses.

STEPHEN D. TUCKER.
